UNITED STATES PATENT OFFICE.

CHARLES A. HIRSCHI, OF ALLEGHENY, PENNSYLVANIA, ASSIGNOR TO THE
PITTSBURG LAMP AND BRASS COMPANY, OF PITTSBURG, PENNSYLVANIA.

DESIGN FOR A CLOCK-FRAME.

SPECIFICATION forming part of Design No. 29,300, dated September 6, 1898.

Application filed July 6, 1898. Serial No. 685,283. Term of patent 3½ years.

To all whom it may concern:

Be it known that I, CHARLES A. HIRSCHI, a resident of Allegheny, in the county of Allegheny and State of Pennsylvania, have invented a new and original Design for Frames; and I do hereby declare the following to be a full, clear, and exact description thereof.

My invention relates to a design for a clock-frame or similar article.

My design is illustrated by the accompanying drawing, and I will describe it with reference to same. The frame has the central opening *a*, and around said opening are the balls or beads *b*. At the top of the frame is the wreath *c*, which incloses the head and shoulders of a man *d*, in uniform. Sloping down from the wreath *c* are the shoulders *e*. The shoulders are supported by the concave pillars *f*, which meet with the convex por-

tions *g*, which are curved around at the lower ends to form the bases *h*. Below the opening *a* on the face of the frame are the cannon *i*, crossed, with the balls *k* supported thereon. The shield *l* is arranged to the right of the cannon. The gun *m*, the sword *n*, and anchor *o*, crossing one another, are arranged to the right of the shield.

What I claim is—

The design for a clock-frame or similar article substantially as herein shown and described.

In testimony whereof I, the said CHARLES A. HIRSCHI, have hereunto set my hand.

CHARLES A. HIRSCHI.
